UNITED STATES PATENT OFFICE.

CHARLES L. MCKENZIE, OF PITTSBURGH, PENNSYLVANIA.

DIPPER CONSTRUCTION.

1,009,254.

Specification of Letters Patent. Patented Nov. 21, 1911.

Application filed June 8, 1911. Serial No. 631,982.

To all whom it may concern:

Be it known that I, CHARLES L. MCKENZIE, a citizen of the United States, and resident of Pittsburgh, county of Allegheny, State of Pennsylvania, have invented certain new and useful Improvements in Dipper Construction; and I do hereby declare the following to be a full, clear, and exact description of the invention, such as will enable others skilled in the art to which it appertains to make and use the same.

This invention relates to dipper excavators, and especially to improvements in the construction shown in my U. S. Patent No. 967,819, dated August 16, 1910.

The improvements relate primarily to the form and arrangement of the washers which embrace the cutting teeth at the dipper edge, and it is aimed to protect more fully the reinforcing bar extending transversely beneath the teeth, or the forward edge of the dipper bottom in case such bar is not employed, or, again, to protect more fully the front edges of the bar and the dipper bottom as well. Washers constructed in accordance with this invention are applicable to all the uses indicated in the aforesaid patent, more particularly as regards the use or omission of the reinforcing bar at the dipper edge.

A perhaps even more important object of the present invention is to provide a construction in which the above mentioned washers are so shaped as to take an active part in cutting into and dipping or scooping up the material. In other words, the improved washers facilitate to a marked degree the digging of the dipper or scoop into the material, thereby assisting the cutting teeth, and moreover they have the advantage over the washers used in my prior construction that they facilitate the entrance of the dipper into the material at the proper angle and throw the material in such a direction that it will be scooped up in the dipper.

In the accompanying drawings, Figure 1 is a fragmentary perspective view of a dipper provided with my improvements; Fig. 2 is a vertical longitudinal section through the dipper bottom and its adjunctive parts; Figs. 3, 4 and 5 are detail views of the washer shown in Figs. 1 and 2; Fig. 6 is a fragmentary front elevation of a dipper

having washers of modified form; Fig. 7 is a top plan view of the parts shown in Fig. 6; Figs. 8, 9 and 10 are details of the modified washer, and Fig. 11 is a detail view showing how the individual washers can be combined in a single bar.

Referring to the drawings, and particularly to Figs. 1 to 5, A denotes a dipper or scoop of any desired shape, having U-shaped holder plates 14 applied to the bottom at the forward edge portion thereof, substantially as shown in the above mentioned patent. 15 are the teeth inserted in said holder plates, as before, and 16 is the common reinforcing bar extending across the forward edge of the dipper bottom, beneath the teeth and their holders. This bar, however, may be omitted, as previously intimated. The holder plates 14 preferably extend out beyond the forward dipper edge, as shown, but this is likewise a non-essential feature.

The present invention concerns itself especially with the washers which embrace the forward ends of the cutting teeth, which washers are indicated at 17 in Figs. 1 to 5. In the form shown in these views, each washer 17 is of pyramidal shape, having a thin edge or edges 18 disposed toward the front and sloping backward to a comparatively thick rear edge 19. The opening or bore extending through the washer is shaped to correspond with the cross section of the corresponding cutting tooth which the washer embraces. The thickened rear portions 19 of the washers are of sufficient size to cover fully and thereby efficiently protect the forward edges of the corresponding holder plates 14, with which forward edges the rear faces of such washers are in contact or abutment. Moreover, according to this invention the keeper plates are not only protected by the washers in the manner described, but the washers also serve to protect the forward face of the reinforcing bar 16 or in case such bar is omitted, of the dipper bottom itself. This is effected by forming lateral wings 20 on opposite sides of each washer. In the embodiment shown in Figs. 1 to 5 these wings cover the portions of the reinforcing bar which are not covered by the main portions or bodies of the washers, so that, if the rear portions of the washer bodies are extended

downwardly to such an extent as to be in contact with the forward edge of the reinforcing bar throughout the width of the latter, as shown in Fig. 2, the entire forward face or edge of such bar or equivalent part will be fully covered and protected by the washer elements.

In order to expedite the entrance of the washer 17 into the material to be excavated, 10 the forward edges of the wings 20 converge toward the front of the washer, as best shown in Fig. 4. In Fig. 3, such sloping or inclined edges are indicated at 21 and it will be noted that they decrease in width toward 15 the front of the washer so as to afford a relatively thin cutting edge where the forward portion of each wing joins the washer body. This also facilitates to a considerable degree the entrance of the dipper into the 20 material. The thickened rear portions of the wing edges 21 merge into or join suitably shaped side surfaces 22 of the wings and these surfaces of each washer abut corresponding surfaces at opposite sides, so 25 that the bar 16 is entirely covered, as previously mentioned. With this construction, it will be noted that the wings of the several washers form in conjunction a saw-like working edge between the dipper teeth, 30 whereby the digging of the dipper into the material is considerably facilitated. The scooping of the material into the dipper is also made more easy by the upward inclination of the top surfaces of the wings 20 35 which are preferably connected with the side portions of the washer bodies by curved surfaces of appropriate shape, as shown in Fig. 3. The dipper teeth may be held in their sockets by friction or otherwise, and 40 the washers are shown as held on the forward ends of the teeth by friction, although appropriate fastening means may be used if desired.

In the construction shown in Figs. 6 to 10, 45 the washers are so shaped as to cut the material even more effectively than the washers previously described. In this case, the washer bodies 23 are of the general pyramidal shape previously indicated, but the 50 wings 24 are not sloped inward at their front edges. On the other hand, they are provided with front edges 25 directed parallel to the forward edge of the dipper bottom. The wings of adjacent washers are in 55 abutment at their side faces, as before. By beveling the wings so that the front edges 25 are comparatively thin in comparison to the rear edges 26, the surface presented by all of the wings in conjunction may be given 60 a knife like shape, so as to cut easily into such materials as hard clay, compressed earth, shale and the like. In this form of the invention, I prefer to make the bottom surfaces 27 of the wings substantially flush 65 with the bottom surface of the dipper, as

this shape of wing tends to throw the material into the dipper instead of causing the latter to ride over the material.

In Fig. 11 I have shown washers like those just described combined in a single element or washer bar, which can be readily slipped over all of the cutting teeth at the same time. The only difference over the construction shown in Figs. 6 to 10 is that instead of being separate the individual washers have their wings integrally joined to each other, as shown at 28. It is obvious that the washers of Figs. 1 to 6 may likewise be joined to form a common bar, and that other washers embodying my improvements may be formed into a single structure to embrace the dipper teeth and protect the forward edge of the dipper. Of course still further modifications of the structure may likewise be adopted without digressing from the invention as defined in the claims.

What I claim is:—

1. In a dipper construction, a dipper bottom, teeth extending forward thereof, and cutting means embracing and extending between the teeth. 90

2. In a dipper construction, a dipper bottom, teeth extending forward thereof, and means embracing said teeth and extending 95 lengthwise of the dipper edge completely across the spaces between the teeth.

3. In a dipper construction, a dipper bottom, teeth extending forward thereof, and cutting means embracing the teeth and extending lengthwise of the forward dipper edge across the spaces between the teeth. 10

4. In a dipper construction, a dipper bottom, teeth extending forward thereof, and washers embracing the teeth and shaped to 10 cover the forward dipper edge between the teeth.

5. In a dipper construction, a dipper bottom, teeth extending forward thereof, and washers embracing the teeth and shaped to 11 cover the forward dipper edge between the teeth, said washers increasing in thickness from front to rear.

6. In a dipper construction, the combination of a dipper bottom, teeth projecting forward thereof, and washers embracing said teeth and having lateral projecting portions protecting the forward edge of the dipper bottom. 11

7. In a dipper construction, the combination of a dipper bottom, teeth applied to the same, and washers embracing the forward portions of the teeth and having portions completely covering the forward dipper edge between the teeth. 12

8. In a dipper construction, the combination of a dipper bottom, teeth applied thereto, and washers embracing the teeth and having lateral wings protecting the front dipper edge between the teeth. 12

9. In a dipper construction, the combination of a dipper bottom, teeth applied thereto, and washers embracing the teeth and having lateral wings protecting the front 5 dipper edge between the teeth, said wings being tapered to facilitate cutting into the material being excavated.

10. In a dipper construction, the combination of a dipper bottom, holder plates applied to one surface thereof, teeth extending forwardly out of said holder plates, and substantially pyramidal washers embracing the forward ends of said teeth and having lateral wings lying substantially in the 15 plane of the dipper bottom.

11. In a dipper construction, the combination of a dipper bottom, holder plates applied to one surface thereof, teeth extending forwardly out of said holder plates, and 20 washers embracing the forward portions of said teeth and having laterally directed portions lying substantially in the plane of the dipper bottom and extending across the spaces between said teeth, said portions decreasing in thickness toward their front 25 edges.

12. In a dipper construction, the combination of a dipper bottom, a holder plate applied to one surface thereof, a tooth extending forwardly out of said holder plate, a washer embracing the forward portion of said tooth and covering substantially the whole forward edge of the holder plate, said washer being of substantially pyramidal form and extended at its lower portion completely across the forward dipper edge, and wings on said washer projecting 35

laterally at opposite sides thereof and lying substantially in the plane of the dipper bottom.

13. In a dipper construction, the combination of a dipper bottom, a holder plate applied to one surface thereof, a tooth inserted in said plate and projecting forwardly thereof, a reinforcing bar extending under 40 said tooth at the forward dipper edge, and a substantially pyramidal washer embracing the forward portion of said tooth, said washer having lateral wings, as described, and having its rear surface extended completely across and in abutment with the forward face of the reinforcing bar.

14. As an article of manufacture, a substantially pyramidal dipper tooth washer having laterally projecting wings. 45

15. As an article of manufacture, a substantially pyramidal dipper tooth washer having projecting wings at opposite sides, increasing in thickness from front to rear. 50

16. As an article of manufacture, a dipper tooth washer having a substantially pyramidal body with an interior bore, the forward edge of the body being thin at one end of the bore and tapering to a thick portion at the rear of the bore, and lateral 55 wings on said body, increasing in thickness from front to rear, as described.

In testimony whereof I affix my signature, in presence of two witnesses.

CHARLES L. MCKENZIE.
